US0D1025057S

(12) **United States Design Patent** (10) **Patent No.:** **US D1,025,057 S**
(45) **Date of Patent:** **** Apr. 30, 2024**

(54) **HEADSET**

(71) Applicant: **RealWear, Inc.**, Vancouver, WA (US)

(72) Inventors: **Stephen Pombo**, Campbell, CA (US); **Christopher Parkinson**, Richland, WA (US); **George Hines**, San Francisco, CA (US)

(73) Assignee: **RealWear, Inc.**, Vancouver, WA (US)

(**) Term: **15 Years**

(21) Appl. No.: **29/798,780**

(22) Filed: **Jul. 9, 2021**

(51) **LOC (14) Cl.** **14-02**

(52) **U.S. Cl.**

USPC **D14/372**

(58) **Field of Classification Search**

USPC D14/372, 205, 192; 381/380-381; 359/630

(57) **CLAIM**

The ornamental design for a headset, as shown and described.

DESCRIPTION

FIG. 1 is a top view of a headset showing the new design; FIG. 2 is a bottom view thereof; FIG. 3 is a front view thereof; FIG. 4 is a back view thereof; FIG. 5 is a right side view thereof; FIG. 6 is a left side view thereof; FIG. 7 is a front left perspective view thereof; FIG. 8 is a front right perspective view thereof; FIG. 9 is a back right perspective view thereof; and, FIG. 10 is a back left perspective view thereof.

The broken lines immediately adjacent the headset housing represent the bounds of the claimed design while all other broken lines depict portions of the headset that form no part of the claimed design.

1 Claim, 8 Drawing Sheets
